[57] CLAIM

The ornamental design for a dispensing cap, as shown
and described.

DESCRIPTION

FIG. 1 is a perspective view of a dispensing cap, showing
my new design;

FIG. 2 is a top plan view thereof;

FIG. 3 is a right side elevational view thereof;

FIG. 4 is a left side elevational view thereof;

FIG. 5 is a front elevational view thereof;

FIG. 6 is a bottom plan view thereof;

FIG. 7 is a bottom perspective view thereof;

FIG. 8 is a front elevational view thereof in a closed
position, the container shown in broken lines for illus-
trative purposes only; and,

FIG. 9 is a perspective view of a second embodiment of
FIG. 1, the difference residing in the smooth side walls.
